Inventor

UNITED STATES PATENT OFFICE.

SALATHIEL C. RUPE, OF CARROLLTON, MISSOURI.

LEMON PRESSER OR SQUEEZER.

SPECIFICATION forming part of Letters Patent No. 447,975, dated March 10, 1891.

Application filed August 13, 1890. Serial No. 361,875. (No model.)

To all whom it may concern:

Be it known that I, SALATHIEL C. RUPE, a citizen of the United States, residing at Carrollton, in the county of Carroll and State of 5 Missouri, have invented a new and useful Lemon Presser or Squeezer, of which the following is a specification.

This invention has relation to lemon pressers or squeezers; and the objects in view are 10 to provide a press adapted to be operated by foot or hand and to successively deliver, cut, and squeeze a series of lemons subjected thereto, eject the skins and pulp, strain the juice, and deliver the same into a waiting receptacle.

Various other objects of the invention will hereinafter appear, and the novel features thereof will be particularly pointed out in the claims.

20 Referring to the drawings, Figure 1 is a perspective of a lemon squeezer or press constructed in accordance with my invention. Fig. 2 is a vertical longitudinal section of the same. Fig. 3 is a similar view, the plunger 25 being lowered as in the act of squeezing or pressing a lemon. Fig. 4 is a detail in perspective of the plunger and its rod. Fig. 5 is a detail in perspective of the reciprocating bucket. Fig. 6 is a similar view of the combined strainer and knife.

Like numerals indicate like parts in all the figures of the drawings.

1 designates a standard mounted upon a suitable base 2. Secured to the front face of 35 the standard at a suitable height thereon is a bracket 3, having a circular opening extending vertically through the same and terminating in the lower end of its opening in a discharge-spout 4. The opposite sides of the 40 bracket are grooved vertically, as at 5, and secured to the same are the lower ends of a pair of opposite vertical guide-rods 6, the upper ends of which terminate in a block 7, secured to the front face and near the upper 45 end of the standard.

8 designates a small bracket located under the discharge-spout 4 and adapted to receive a glass, bucket, or other vessel for the purpose of holding the juice as extracted.

50 9 designates a strainer, cup, or disk having an annular recess upon its under side, so as to fit within the opening of the bracket 3.

The upper face of the strainer is dished or concaved, as shown, and minutely perforated and provided with an upwardly-disposed 55 knife or blade 10. The opposite edges of the strainer have grooves 11, which register with the grooves 5 of the bracket and form a continuation of the same. Set in a recess 12, formed in the front face of the standard 1, 60 immediately above the strainer, is a spring ejecting-tongue 13, the lower end of which curves outward and terminates above the strainer.

14 designates a sliding bucket centrally 65 bored throughout its vertical length and having grooves 15, whereby it is adapted to receive and slide vertically between the opposite guide-rods 6. The bottom of the bucket 14 is provided with an annular flange 16, 70 which fits within the concaved upper face of the strainer 9, and said bucket rests upon the strainer when in its normal position.

17 designates a yoke, the opposite ends of which are provided with recesses or grooves 75 to receive the opposite guides 6. From the upper end of the yoke extends a plunger-rod 18, the upper end of which reciprocates through an opening 19, formed in the block 7. From the under side of the yoke depends 80 a head 20, cylindrical in cross-section and of a size adapted to fit within the bore of the bucket 14. Secured to one end of the yoke 17 is a spring-latch 21, the lower end of which rests within an inclined recess 22, formed in 85 the side of the standard 1.

23 designates a hopper supported by supporting-braces 24 upon the opposite guides 6 and on about a level with the upper end of the bucket 14. The rear side of the hopper 90 is open and its opposite edges provided with ways 24'. The bottom 25 of the hopper is inclined and is located at the lower end of the ways, and at the upper end of said ways there is journaled a loose roller 26, over which is 95 suspended an apron 27, one end of which is made fast to the front edge of the yoke 17, and the opposite end is connected to a gate 28, mounted for sliding in the opposite ways 24' of the hopper.

100 29 designates a lever for operating the device, said lever being pivoted, as at 30, to the standard 1. A bail 31 is connected to the yoke 17 and at its lower end to the foot-lever

29, so that any movement upon the part of the foot-lever causes a similar movement upon the part of the yoke, plunger, and pressing-head 20.

- 5 32 designates a perforated guide-bracket secured to the standard 1 below the lever 29, and in said guide-bracket is mounted a guide-rod 33, the upper end of which is provided with a shallow recess 34 for receiving the 10 lower edge of the lever 29, and is connected to said lever by means of a link 35. Encircling the rod 33 between the bracket and lever 29 is a coiled spring 36, which maintains the lever normally in a raised position.
- 15 In operation the hopper is filled with lemons, one of which is permitted to roll into the bucket 14 and down upon the knife of the strainer. This admission of a lemon is caused by a depression of the foot-lever, a consequent lowering of the pressing-head and yoke, and an opening of the gate 28. The foot-lever being released, the parts resume their 20 normal position and the machine is ready for operation. The foot-lever being depressed 25 against the tension of the spring 36, the yoke, guide-rod, and pressing-head 20 descend, as does also the spring-latch 21. As the head descends it enters the bucket, which is pressed snugly upon the strainer, so that no juice may 30 escape, and said head forces the lemon upon the knife, which knife serves to split the same, at the same time forcing the spring 13 to the rear out of its path. Further pressure being exerted, the juice is extracted, passing 35 through the strainer and bracket and through the discharge-spout. By this depression of the head another lemon has been delivered from the hopper, so that when the foot-lever is released and the parts are raised or ele- 40 vated a new lemon rolls into the bucket. As the yoke descends it will be observed that the inclined recess 22 permits the latch 21 to take under the lower end of the bucket, so that when the yoke ascends the bucket is 45 elevated from off the strainer, and the spring-tongue 13 being liberated serves to eject the rind. When the spring-latch has reached the upper portion of its recess, it is forced from under the bucket and the latter drops 50 to its normal position, in which it is supported by the spring-tongue 13, and receives the fresh lemon, the operation thus being continued and lemons successively cut and squeezed, as will be apparent.

55 Having described my invention, what I claim is—

1. In a lemon-press, the combination, with a perforated strainer-cup, a standard for supporting the same, and a superimposed knife, 60 of a reciprocating bucket mounted above the strainer, a reciprocating plunger having a presser-head, means for raising and lowering said head, and a spring-ejector extending from the standard and adapted to be compressed by the bucket and liberated by the 65 upward movement thereof, substantially as specified.

2. In a lemon-press, the combination, with a standard, a perforated strainer mounted in front of the standard, a reciprocating bucket 70 centrally bored and arranged over the strainer, an ejecting spring-tongue secured to the standard and adapted to be depressed by the bucket, of means for raising the bucket and liberating the same, a reciprocating plunger 75 terminating at its lower end in a presser-head, and means for raising and lowering the plunger, substantially as specified.

3. In a lemon-press, the combination, with a standard, a strainer, and a bucket mounted 80 above the strainer and having a central opening throughout its length, of a hopper located at one side of the bucket and provided with ways, a reciprocating plunger terminating in a presser-head adapted to be received by the 85 bucket, a sliding gate or cut-off mounted in the ways, a loose roller journaled above the ways, and a flexible connection between the presser-head and the gate, said connection being passed over the roller, substantially as 90 specified.

4. In a lemon-press, the combination, with a standard, a bracket having an opening terminating in a discharge secured to the face of the standard, opposite vertical guides rising from said bracket, and a strainer having a knife mounted upon the bracket, of a bucket having opposite grooves to receive the guides, a central opening and adapted at its lower end to fit the strainer, a spring-tongue secured to the standard and extending over the strainer, a block connecting the upper ends of the guides and having an opening, a plunger mounted for reciprocation in the opening, a yoke grooved at its ends to embrace the 105 guides and connected with the plunger, a presser-head adapted to fit the bucket mounted on the lower end of the plunger, a spring-latch secured to one end of the yoke and adapted to ride in an inclined recess formed 110 in the edge of the standard and adapted to take under the lower end of the bucket and elevate the same, and means for reciprocating said plunger, substantially as specified.

5. The combination, with the standard, the 115 strainer, the knife, and reciprocating plunger, its guides and yoke, of a foot-lever pivoted in the standard, a bail connecting the yoke with the foot-lever, a perforated bracket located below the lever, a guide-pin mounted 120 for reciprocation in the bracket, bifurcated at its upper end to loosely embrace the lever, a link connecting said pin to the lever, and a coiled spring encircling the pin and interposed between the lever and bracket, substantially as specified.

6. The combination, with the standard, the strainer, the reciprocating plunger, and means for operating the same, of a hopper located 125 above the standard and provided with opposite ways, a gate or cut-off mounted in said ways, and means for operating or raising said gate at each downward reciprocation of the plunger, substantially as specified.

7. In a lemon-press, the combination, with
a strainer, a knife, a superimposed reciprocating
bucket, and a hopper having a gate and
adapted to deliver lemons to the strainer, of
5 a plunger having the presser-head and mechanism
for depressing the head, raising the
gate, and operating the bucket, substantially
as specified.

In testimony that I claim the foregoing as

my own I have hereto affixed my signature in to
presence of two witnesses.
